UNITED STATES PATENT OFFICE.

FRANK KRABAL, OF PITTSBURG, PENNSYLVANIA.

MACHINE FOR FORMING AND PRINTING BUTTER CAKES.

SPECIFICATION forming part of Letters Patent No. 634,300, dated October 3, 1899.

Application filed April 1, 1899. Serial No. 711,369. (No model.)

To all whom it may concern:

Be it known that I, FRANK KRABAL, a citizen of the United States, residing at Pittsburgh, in the county of Allegheny and State of Pennsylvania, have invented a new Improvement 5 in Machines for Forming and Printing Butter Cakes, of which the following is a specification.

My invention relates to an apparatus for 10 forming and printing butter cakes.

Heretofore in the formation of these butter cakes for table use it was customary to use a hand-mold to stamp the cake of butter. This required manual insertion of the butter within 15 the mold by hand and the removing of the same from the mold in like manner, so making the operation tedious, lengthy, and unsatisfactory, as well as not making a uniform cake, as the butter cake would be injured 20 somewhat in its removal from the mold.

The object of my invention is to provide such a form of apparatus in which the butter can be fed thereto in a lump or heap and the butter cakes formed and printed in any design required at one and the same operation 25 and in a cheap and rapid manner without waste or injury to the cake whatever.

My invention consists, generally stated, in the novel arrangement, construction, and combination of parts, as hereinafter more specifically set forth and described, and particularly pointed out in the claims.

To enable others skilled in the art to which my invention appertains to construct and use 35 the apparatus, I will describe the same more fully, referring to the accompanying drawings, in which—

Figure 1 is a side view of the apparatus. Fig. 2 is a top view thereof. Fig. 3 is a side 40 view, partly in section, of the forming-roll, showing a portion of the printing-roll; and Fig. 4 is an enlarged sectional view of one of the forming-cups removed from the forming-roll.

Like numerals herein indicate like parts in each of the figures of the drawings.

As illustrated in the drawings, 1 represents the apparatus, which is provided with the supporting-frame 2, composed of the two standards 3 3' and held together in any suitable manner. Between the standards 3 3' is the forming-roll 4, which is preferably formed of

wood, and is mounted upon the shafts or trunnions 5 5', journaled within the standards 3 3'. The forming-roll 4 is provided with 55 a number of openings or seats 6 around its periphery, which communicate with the central cavity or hollow portion 4' of the roll 4. Secured within each of the seats 6 are the cake-forming boxes 7, which are preferably 60 formed of metal, open at both ends, and have a flange 7' at the other end thereof, which is adapted to fit within a seat in the periphery of the forming-roll 4 and be secured thereto by means of bolts 8', passing through openings 8 in said flange 7' and entering said roll 4. Mounted within each one of the boxes 7 are the sliding boxes 9, which are preferably 65 formed of metal and provided with closed outer ends 9' to form the bottom of the mold 70 10 in the boxes 7. These sliding boxes 9 are provided at their inner ends with the flanges or lugs 11, which extend out from the sides of the boxes 9 and travel within slots 12, formed on the inner end of the forming-boxes 7. Pressing loosely against the rear face of each one of the closed ends 10 of the sliding boxes 9 are the sliding bars 13, which fit within the 75 sliding boxes 9 and extend across the hollow portion 4' of the roll 4. These bars 13 are provided with the bent or offset portions 14 at 80 their inner ends within the boxes 9, and their outer or opposite ends are adapted to pass out through openings 16 between the seats 6, so as to extend beyond the periphery of said 85 roll 4. The sliding bars 13 are staggered within the roll 4, and the bent or offset portions 14 thereon permit a number of them to be used and pass each other within the narrow hollow portion 4' of said roll 4. 90

Supported between the standards 3 3' on the same horizontal axis as the forming-roll 4 is the operating and printing roll 17, which is preferably formed of wood and is mounted upon shafts or trunnions 18 18', journaled 95 within standards 3 3'. This roll 17 is provided with a series of pins 19, secured within the roll 17, which are staggered or adapted to break joint with each other and extend out a sufficient distance from the periphery 100 of said roll 17 so as to engage with the ends 15 of the sliding bars 13 in the forming-roll 4. The roll 17 can also be provided on its periphery with any suitable print or design,

such as is shown at 20, for printing or forming a design on the roll 17 opposite molds 10 in the boxes 7 and can be either indented within or raised above the periphery of said roll 17, as desired. Mounted upon the trunnion 18 of the roll 17 is a gear-wheel 21, which is adapted to mesh with a like gear-wheel 22 on the trunnion 5 of the roll 4, and a handle 23 is also mounted upon the trunnion 18 for operating the apparatus.

A chute 24 is secured to the standards 3 3' at one end of the apparatus beyond the forming-roll 4, and a wire scraper 25 is secured to said standards 3 3' above the chute 24 for removing the butter cakes from the bottom 9' of the mold 10. A hopper 26, having an opening 26', is secured to the standards 3 3' over the pass 27, between the rolls 4 and 17, for the insertion of the butter.

The operation of my improved apparatus for forming and printing butter cakes is as follows: The batch of butter to be formed into cakes is placed within the opening 26' in the hopper 26, and the operator in turning the handle 23 will cause the gear-wheels 21 22, meshing with each other, to revolve, and being secured to the trunnions 18 and 5 of the rolls 17 and 4 will revolve said rolls 17 and 4. As these rolls 17 and 4 are revolved the butter will be drawn in or fed to the pass 27 between the rolls 17 and 4, and a sufficient amount will enter the mold 10 as it comes under the opening 26' in the hopper 26. During the further revolution of the rolls 17 and 4 this mold 10, being filled with butter, will pass around with the roll 4, and when it reaches the central or horizontal axis of the rolls 17 and 4 will meet with one of the prints or designs 20 on the roll 17 at that point, and said print or design 20 will be formed on the top of the butter within such mold 10. Each of the molds 10 in the roll 4 as they arrive under the opening 26' in the hopper 26 are filled with butter from the hopper 26, and when they arrive at the central horizontal axis the print or design 20 is printed on the face of the butter in like manner, and as each one of the outer ends 15 on the sliding bars 13 in the roll 4 arrive at such horizontal axis of the rolls 17 and 4 they will be met by each one of the pins 19 in the roll 17, which will act to force its particular sliding bar 13 through the roll 4 and with it the particular closed end 9' of its sliding box 9, engaging with said bar 13 a sufficient distance to allow such closed end 9' to be pushed out through the mold 10, so that the closed end 9' is flush with the face or periphery of said roll 4. This will cause the butter cakes formed in the molds 10 to be brought flush with the face of the roll 4 and adhere to the bottom or closed ends 9', forming the mold 10, and as such cakes arrive at the wire scraper 25 they will be caught thereby and removed from the end 9' and face of the roll 4, so that they can slide down the chute 24 and drop into any suitable recepta-

cle. During the further revolution of the roll 4 as each one of the sliding bars 13 assumes a vertical position it will drop back by 70 gravity and with it its particular sliding box 9 to its position required to form the mold 10 within the box 7, so that it can pass under the hopper 26 and be filled with butter through the opening 26' therein in order to form the 75 cake when it arrives at the horizontal axis of the rolls 17 and 4 and is met by the print or design 20 on the roll 17, and at the same time one of the sliding bars 13 is met by its particular pin 19 in the roll 17 to force out 80 the end 9' through the mold 10 to free from such mold 10 one of the butter cakes previously made, as above described. During the outward movement of the sliding boxes 9 through the boxes 7 by the sliding bars 13 85 the distance the end 9' on the boxes 9 is required to be moved or travel so as to be flush with the periphery of the roll 4 is regulated by the flanges or lugs 11 on the boxes 9 striking against the closed ends of the slots 12 in 90 the boxes 7.

It will thus be seen that my improved apparatus for forming and printing butter cakes is cheap and simple in its construction and operation, and practical experience in 95 the use of such apparatus has demonstrated it to be rapid and accurate in its operation of forming cakes of this character. The cakes so formed are uniform in size, and it is obvious that cakes of any material and of 100 any size, design, or shape can be formed by such an apparatus. It is also obvious that cakes can be formed by such an apparatus without the necessity of printing or forming a print or design thereon, if desired. 105

Various modifications in the construction and design of the various parts of the apparatus may be resorted to without departing from the spirit of the invention or sacrificing any of its advantages. 110

What I claim as my invention, and desire to secure by Letters Patent, is—

1. In an apparatus for making butter and like cakes, the combination of a forming-roll having a series of molds therein, and an operating-roll adapted to engage with said forming-roll to press the butter into said molds and expel the cakes therefrom when formed. 115

2. In an apparatus for making butter and like cakes, the combination of a forming-roll having a series of molds therein, sliding bars within said forming-roll engaging with said molds, an operating-roll adapted to engage with said forming-roll to press the butter into 120 said molds, and means on said operating-roll adapted to engage with said sliding bars to expel the cakes from said molds when formed. 125

3. In an apparatus for making butter and like cakes, the combination of a forming-roll having a series of molds therein, a series of sliding bottoms within said molds, a series of sliding bars within said forming-roll engaging 130 with said sliding bottoms, an operating-roll

adapted to engage with said forming-roll to press the butter into said molds, and means on said operating-roll adapted to engage with said sliding bars for pressing out the sliding bottoms to expel the cakes from said molds when formed.

4. In an apparatus for forming butter and like cakes, the combination of a forming-roll, a series of mold-boxes secured in said forming-roll adapted to form molds therein, a series of sliding boxes within said mold-boxes having closed outer ends to form the bottoms of said molds, lugs or flanges on said sliding boxes adapted to engage with slots in said mold-boxes for regulating the movement of said sliding boxes, and an operating-roll adapted to engage with said forming-roll to press the butter into said molds and expel the cakes therefrom when formed.

5. In an apparatus for forming butter or like cakes, the combination of a forming-roll, a series of mold-boxes secured in said forming-roll adapted to form molds therein, a series of sliding boxes within said mold-boxes having closed outer ends to form the bottoms of said molds, lugs or flanges on said sliding boxes adapted to engage with slots in said mold-boxes for regulating the movement of said sliding boxes, a series of sliding bars within said forming-roll engaging with the closed ends of said sliding boxes, an operating-roll adapted to engage with said forming-roll to press the butter into said molds, and means on said forming-roll adapted to engage with said sliding bars for pressing out said sliding boxes to expel the cakes from said molds when formed.

6. In an apparatus for making butter and like cakes, the combination of an operating or printing roll, a forming-roll engaging therewith, a series of molds within said forming-roll, a series of sliding bottoms within said molds, a series of sliding bars within said forming-roll engaging with said sliding bottoms, and a series of pins on said operating or printing roll adapted to engage with said sliding bars to expel the cake from the molds when formed.

7. In an apparatus for making butter and like cakes, the combination of a forming-roll having a series of molds therein, sliding bars within said forming-roll and engaging with said molds, an operating-roll adapted to engage with said forming-roll to press the butter into said molds and with said sliding bars to expel the cakes from said molds when formed, and a series of prints or designs on said operating-roll adapted to engage with said cakes as they are formed or pressed in said molds to form said prints or designs thereon.

8. In an apparatus for making butter and like cakes, the combination of an operating-

roll, a forming-roll engaging therewith, a series of mold-boxes within said forming-roll adapted to form molds therein, a series of sliding boxes within said mold-boxes having closed ends to form the bottom of said molds, a series of sliding bars within said forming-roll and sliding boxes engaging with said closed ends to expel the cake from the molds when formed, said sliding bars having a bent or offset portion within said sliding boxes, and means for operating said sliding bars.

9. In an apparatus for making butter and like cakes, the combination of a housing, a forming-roll journaled on a shaft or trunnions in said housing and provided with a series of molds therein, an operating-roll journaled on a power shaft or trunnion in said housing adapted to engage with said forming-roll to press the butter into said molds and said cakes therefrom when formed, a hopper secured to said housing of said rolls, and a gear-wheel mounted on the power shaft or trunnions of the operating-roll adapted to mesh with a gear-wheel on the shaft or trunnions of the forming-roll to operate the same.

10. In an apparatus for making butter and like cakes, the combination of a housing, a forming-roll journaled on a shaft or trunnions in said housing and provided with a series of molds therein, an operating-roll journaled on a shaft or trunnions in said housing adapted to engage with said forming-roll to press the butter into said molds and expel said cakes therefrom when formed, a hopper secured to said housing above the rolls, a gear-wheel mounted on the shaft or trunnions of the forming-roll adapted to mesh with a gear-wheel on the shaft or trunnions of the forming-roll, and a handle or crank mounted upon the shaft or trunnions of the operating-roll to operate the same.

11. In an apparatus for making butter and like cakes, the combination of housings having a forming-roll journaled therein provided with a series of molds thereon, an operating-roll journaled within said housings adapted to engage with said forming-roll and press the butter into said molds, means within said molds and on said operating-roll for expelling the cakes from said molds when formed, a chute secured to said housings, and a scraper above said chute adapted to engage with the expelled butter cakes to remove the same from the forming-roll.

In testimony whereof I have hereunto set my hand, at Pittsburg, in the county of Allegheny and State of Pennsylvania, this 21st day of February, A D. 1899.

FRANK KRABAL.
